UNITED STATES PATENT OFFICE.

ARTHUR H. FARGO, OF WEST NEWTON, MASSACHUSETTS.

SCRAPING-MACHINE.

1,090,910.

Specification of Letters Patent. Patented Mar. 24, 1914.

Application filed January 17, 1913. Serial No. 742,748.

To all whom it may concern:

Be it known that I, ARTHUR H. FARGO, a citizen of the United States, residing at West Newton, in the county of Middlesex and State of Massachusetts, have invented new and useful Improvements in Scraping-Machines, of which the following is a specification.

This invention relates to scraping machines, the object in view being to provide a practical, easily operated machine for scraping the sides of houses, buildings, bridges, and other structures, for the purpose of removing scale, paint and the like from the surfaces thereof, preparatory to the repainting or otherwise ornamenting the surfaces scraped and cleaned.

The invention contemplates the use of a suspension frame, combined with means for raising and lowering the same, and a scraper mounted to travel back and forth on a substantially horizontal rail carried by the suspension frame, the scraper embodying a motor which is hung below the supporting rail and which is capable of adjustment, so as to bring the scraping member into proper relation to the surface being operated upon, said scraping member being driven by the motor.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation of a portion of a building, showing the scraping machine of this invention in its applied position and relation thereto. Fig. 2 is a front elevation on an enlarged scale, showing the supporting truck, the rail therefor and the motor and scraping member, together with the means for mounting the same. Fig. 3 is a vertical transverse section on the line 3—3 of Fig. 2. Fig. 4 is a side elevation of the mechanism shown in Fig. 2, the supporting rail being in section. Fig. 5 is a view similar to Fig. 4, showing the adjustment of the scraping member with relation to the motor casing. Fig. 6 is a diametrical section through the scraping member shown in Figs. 1 and 2. Fig. 7 is a horizontal section on the line 7—7 of Fig. 6. Fig. 8 is a front elevation of the scraper head, showing also a portion of the motor

casing and the cylindrical scraping member mounted on the tumbling extension of the motor shaft. Fig. 9 is a cross section on the line 9—9 of Fig. 8. Fig. 10 is a detail horizontal section on the line 10—10 of Fig. 2. Fig. 11 is a detail vertical section on the line 11—11 of Fig. 2. Fig. 12 is a horizontal section on the line 12—12 of Fig. 2. Fig. 13 is a vertical cross section through the suspension frame and platform, showing the raising and lowering means and the truck supporting rail in section. Fig. 14 is a side elevation of a scraping band having curved teeth. Fig. 15 is a detail elevation, similar to Fig. 8, showing the endless scraper band and its wheels and other actuating parts removed, and a cylindrical scraping member mounted on the central tumbling shaft.

As shown in Figs. 1 and 2, the machine contemplated in this invention comprises a suspension frame, embodying two open center rectangular end members, each embodying substantially parallel uprights 1 and 2, 80 and top and bottom cross bars 3 and 4, respectively, the end frames referred to forming spaced supports for a platform 5, upon which the operator is enabled to stand, as shown in Fig. 1, for operating the scraping mechanism, hereinafter particularly described.

The end members of the supporting frame are provided with eyes 6 to receive the lower blocks 7 of block and tackle hoisting and lowering means, said block and tackle being supported by hooks 8 adapted to engage the upper part of a building, bridge, or other structure, so as to support the apparatus as a whole therefrom and in close relation to the structure and enable the suspension frame to be raised and lowered in accordance with the work.

Extending longitudinally of the suspension frame is a track rail 9 of inverted T-shape in cross section, as shown in Fig. 4, said rail being rigidly fastened at its opposite extremities to the top cross bars 3 of the end members of the suspension frame, as shown in Figs. 1 and 13. At each extremity of the rail 9 is a stop arm 10, with which the truck, hereinafter described, is adapted to come into contact, so as to prevent the truck wheels from coming into injurious contact with the hoisting and lowering mechanism. Mounted upon the track rail 9 is a truck, embodying a truck frame

11, in the opposite ends of which are journaled truck wheels 12 having their peripheries grooved, as shown in Fig. 4, so as to embrace the upstanding web of the rail 9 5 and prevent displacement of the truck from said rail.

14 designates a motor casing which is mounted to turn on pivots 15 at the lower extremities of a hanger frame, comprising 10 a pair of oppositely arranged hanger arms 16, the upper ends of which are journaled on a yoke 17 in the form of a rod, the opposite ends of which are received in vertically slotted guides 18 extending downwardly from 15 the bottom of the truck frame 11, as illustrated in Fig. 2. The yoke 17 is provided with a central upstanding lug 19 which receives a king bolt 20 carried by the truck frame 11, so that the motor and its casing, together with the scraping member, and all 20 operating and adjusting parts therefor, are supported by means of the king bolt 20, the arrangement described enabling the structure supported by the king bolt to swing and 25 maintain itself in proper position by gravity, in case the supporting rail 9 is not exactly horizontal.

In view of the fact that the hanger frame, consisting of the arms 16, is journaled on 30 the yoke, and the yoke in turn pivotally connected to the truck on an axis at right angles to the axis on which the hanger arms 61 turn, it will be seen that the hanger frame and all parts carried thereby have a universal mounting with relation to the overhead truck and track rail, thus enabling the 35 angle of the hanger frame and the motor and scraping member to be adjusted to suit conditions, such as irregularities in the surface being scraped or cleaned. Such variation in the angle of the parts referred to is well illustrated in Figs. 4 and 5. In Fig. 4, the scraper is shown as operating upon a vertical wall or surface 21, while in Fig. 5, 40 it is shown as operating upon an angular offset 22 in such wall or surface.

Within the motor casing 14 is arranged an electric motor, the shaft of which extends through the top of the casing 14, as 45 best illustrated in Fig. 3, said shaft having connected thereto by a universal joint 24 a tumbling extension 25, on which is mounted the scraping member 26. The tumbling extension 25 of the motor shaft passes through 50 a scraper head bearing 27, in which it is journaled, while pivotally connected to said scraper head at the point 28 is a scraper adjusting hand lever 29, consisting of parallel side bars connected at the lower end of said 55 lever by means of a handle bar 30. Pivotally connected, at 31, to the side bars of the hand lever are rack bars 32 which are connected together at their free ends by a handle bar 33. The rack bars 32 pass

through guides 34 extending from the adjacent side of the motor casing 14, and the teeth of the rack bars 32 are adapted to be moved into and out of engagement with a tooth or projection 35 at the outer end of each guide 34, as illustrated in Fig. 5, the 65 rack bars 32 being normally held in engagement with the teeth 35 by means of springs 36. By means of the construction just described, it will be understood that by grasping the handle bars 30 and 33, and 70 moving the latter so as to disengage the locking rack bars 32, the tumbling extension of the motor shaft may be set at any desired angle with relation to the motor shaft proper, for the purpose of varying the 75 angle of the scraping member in accordance with the angularity of the surface being scraped, as indicated in Figs. 4 and 5.

The motor casing 14 is connected to the scraper head 27 by means of hinges, comprising the upper and lower members 37 and 38, respectively, connected together by pivots or hinge pins 39. These hinge members 37 and 38 are bolted or otherwise secured rigidly to the scraper head and motor 90 casing, respectively, and the hinges are braced at opposite sides thereof by means of plates 40, as illustrated in detail in Fig. 12, and shown in side elevation in Fig. 5, said 95 bracing plates being rigidly connected to the scraper head 27 by screws 41, or the equivalent thereof.

If desired, the motor casing 14 may be locked in fixed relation to the hanger arms 16 by a locking bolt 42 passing through one 100 of the hanger arms and entering a socket 43 in the motor casing, as best illustrated in Figs. 2 and 4, said locking bolt 42 being normally pressed inwardly into locking engagement with the motor casing by means 105 of a coiled expansion spring 44, as shown in Fig. 2. By withdrawing the locking bolt 42, the motor casing is unlocked and may be swung to any desired angle with relation to the hanger frame, as illustrated in Figs. 4 110 and 5, for bringing the scraping member into the desired relation to the surface being operated upon.

The scraping member, in the preferred embodiment thereof, comprises a sprocket 115 wheel 45 fast on the tumbling extension shaft 25, and a sprocket chain 46 which passes around the wheel 45 and also around other sprocket wheels 47 fast on shafts 48 at opposite sides of the tumbling shaft 25, as shown in Fig. 7. On the same shafts 48 with the sprocket wheels 47 are band wheels 49, around which passes a band 49' carrying on its outer face scrapers or teeth 50 which are adapted to revolve around the wheels 49 with the endless belt and work in contact 120 with the surface being treated.

Instead of employing the endless band or

belt scraper illustrated in Figs. 6 and 7, a single cylindrical scraping member 51 may be employed, as shown for example in Fig. 8, said scraper being mounted fast on the 5 tumbling shaft 25, and being provided with spirally arranged scraping teeth 52. For broad flat surfaces, the scraper member illustrated in Figs. 6 and 7, is preferred, as it will operate with greater rapidity, but 10 where the device has to be used in small corners and turns, the single cylindrical scraping member 51 may be used to a better advantage.

In order to control the speed of the motor, 15 a rheostat 53 is mounted on the handle bar 30, as shown in Figs. 1 and 2, the current wires shown at 54 and 55 leading to said rheostat and from thence to the motor 23. Any desired form or construction of rheostat 20 may be employed for this purpose, and by arranging the same on the handle bar 30, it is always accessible to the operator, who may thereby increase or diminish the speed of the scraping element.

25 At times, it is important to stop the truck 11 and hold the same stationary. In order to do this, brake shoes 56 are provided for the truck wheels 12, and slung adjacently thereto by means of supporting links 57 30 connected to the truck frame. Extending inwardly from the brake shoes 56 are connecting rods 58 which pass through eyes 59 on the lower ends of the guides 18, in which the opposite ends of the yoke rod 17 are 35 capable of moving up and down, as illustrated in detail in Fig. 11. To the inner ends of these connecting rods 58 are pivotally attached brake levers 60 extending across each other and provided with slots 61 40 to receive a pin 62 carried by the upper end of a handle 63. By pulling downwardly on the handle 63 and correspondingly depressing the pin 62, the levers 60 are correspondingly depressed, and the opposite ends there- 45 of are forced apart, thereby sliding the connecting rods 58 and forcing the brake shoes 56 against the wheels 12. Normally, the brake shoes are held inactive by means of a coiled contractile spring 64, one end of 50 which is connected to the pin 62, while the opposite end is connected to a fixed point on the truck frame 11. When the operator wishes to hold the truck stationary, he grasps the handle 63 and draws the same 55 downwardly, until the brake shoes are set against the wheels. In order to release the truck, it is only necessary to release the handle 63.

Where the larger scraping member, illus- 60 trated in Figs. 6 and 7, is employed, and in order to accommodate such scraping member, the hanger arms 16 are offset outwardly, as shown at 65 in Fig. 2. The wires 53 and 54 may be carried through supporting eyes

or fairleaders 66 on one of the end members 65 of the suspension frame, as shown in Fig. 1, and thence off to a suitable source of electric energy.

From the foregoing description, it will now be understood that the operator stands 70 on the platform 5 of the suspension frame, and that said suspension frame is capable of being raised and lowered by means of the hoisting mechanism, illustrated and referred to in the description. The suspension frame 75 carries the supporting track rail 9, and the truck is movable lengthwise of the said rail, so that the scraping mechanism may be shifted along a substantially horizontal path and in the desired proximity to the surface being 80 operated upon. It will also be seen that the hanger frame which supports the motor and scraping member, and the driving mechanism, is hung from the overhead truck, and that it is capable of universal swinging 85 movement, so that it may be rocked to one side or the other or toward and away from the wall or other surface. Furthermore, the motor and its casing may be tilted with respect to the hanger frame, and the tumbling 90 shaft may be adjusted by means of the scraper head to any desired angle for the proper presentation of the scraping member to the surface being operated upon. The handle bar 30 may be used as a presser bar 95 for holding the scraping member with any desired pressure against the wall or other surface, and may also be used for drawing the scraping member out of contact with said surface, as may be required. Furthermore, the angular relation of the tumbling 100 shaft to the motor shaft may be fixed by means of the locking rack, comprising the rack bars 33, as hereinabove described. The rheostat 53 is shown as provided with a 105 suitable operating handle 67.

Instead of the straight teeth 50, shown in Fig. 2, on the endless scraping band 49', the teeth may be given a compound curve, as shown at 50' in Fig. 14.

110 Referring to Fig. 8, when the cylindrical scraping member 51 is employed, without removing the endless scraping band 49', a casing 68 will be placed around the endless band 49', so as to protect said band and the actuating mechanism thereof. It is, however, preferred, when using the cylindrical scraping member 51, to remove the endless scraping band, and its actuating parts, as shown in Fig. 15, and place the cylindrical 115 scraping member 51 directly on the extension 25 of the central tumbling shaft. The arrangement referred to is clearly illustrated in Fig. 15.

120 Springs 69 may be used, as shown in Fig. 125 2, for holding the brake shoes 56 normally out of contact with the wheels 12, thereby assisting the spring 64 which acts to draw

upwardly on the operating handle 63, as previously described.

What is claimed is:

1. A portable scraping machine comprising a suspension frame, overhead supporting raising and lowering means therefor, a workman's platform on said frame, a horizontal track rail carried by the suspension frame above said platform, a wheeled truck 10 movable on said rail, a motor driven scraper suspended below and pivotally supported by said truck, and brake mechanism for holding the truck stationary.

2. A portable scraping machine comprising 15 a suspension frame, overhead supporting raising and lowering means therefor, a workman's platform on said frame, a horizontal track rail carried by the suspension frame above said platform, a wheeled truck 20 movable on said rail, a motor driven scraper suspended below and pivotally supported by said truck, and manually controlled means for setting the brake mechanism.

3. A portable scraping machine comprising 25 a suspension frame, overhead supporting raising and lowering means therefor, a workman's platform on said frame, a horizontal track rail carried by the suspension frame above said platform, a wheeled truck 30 movable on said rail, a motor driven scraper suspended below and pivotally supported by said truck, a hanger frame by which the scraper is supported, and a supporting yoke pivotally mounted on the truck and having 35 the hanger frame pivotally connected thereto.

4. A portable scraping machine comprising 40 a suspension frame, overhead supporting raising and lowering means therefor, a workman's platform on said frame, a horizontal track rail carried by the suspension frame above said platform, a wheeled truck 45 movable on said rail, a motor driven scraper suspended below and pivotally supported by said truck, a hanger frame for the scraper, a yoke pivotally mounted on the truck and having the hanger frame pivotally connected thereto, and a king bolt connecting said yoke pivotally with the truck.

5. A portable scraping machine comprising 50 a suspension frame, overhead supporting raising and lowering means therefor, a workman's platform on said frame, a horizontal track rail carried by the suspension frame above said platform, a wheeled truck 55 movable on said rail, a motor driven scraper suspended below and pivotally supported by said truck, a motor, a motor supporting frame pivotally mounted on the truck, and 60 means for tilting said scraper.

6. A portable scraping machine comprising 65 a suspension frame, overhead supporting raising and lowering means therefor, a workman's platform on said frame, a horizontal track rail carried by the suspension

frame above said platform, a wheeled truck movable on said rail, a motor driven scraper suspended below and pivotally supported by said truck, a motor, a motor supporting frame pivotally mounted on the truck, and 70 means for tilting the scraper relatively to its actuating motor.

7. A portable scraping machine comprising 75 a suspension frame, overhead supporting raising and lowering means therefor, a workman's platform on said frame, a horizontal track rail carried by the suspension frame above said platform, a wheeled truck 80 movable on said rail, a motor driven scraper suspended below and pivotally supported by said truck, a hanger frame connecting the scraper pivotally with the truck, means for tilting the scraper relatively to the hanger frame, and means for maintaining the tilt of the scraper.

8. A portable scraping machine comprising 85 a suspension frame, overhead supporting raising and lowering means therefor, a workman's platform on said frame, a horizontal track rail carried by the suspension 90 frame above said platform, a wheeled truck movable on said rail, a motor driven scraper suspended below and pivotally supported by said truck, a hanger frame pivotally supported by the truck, and a motor casing 95 pivotally supported by the hanger frame.

9. A portable scraping machine comprising 100 a suspension frame, overhead supporting raising and lowering means therefor, a workman's platform on said frame, a horizontal track rail carried by the suspension frame above said platform, a wheeled truck 105 movable on said rail, a motor driven scraper suspended below and pivotally supported by said truck, a hanger frame pivotally supported by the truck, a motor casing pivotally supported by the hanger frame, and means for locking the motor casing to the hanger frame.

10. A portable scraping machine comprising 110 a suspension frame, overhead supporting raising and lowering means therefor, a workman's platform on said frame, a horizontal track rail carried by the suspension frame above said platform, a wheeled truck 115 movable on said rail, a motor driven scraper suspended below and pivotally supported by said truck, a hanger frame pivotally supported by the truck, a motor casing pivotally supported by the hanger frame, and 120 means for adjusting the angle of the motor casing relatively to the hanger frame.

11. A portable scraping machine comprising 125 a suspension frame, overhead supporting raising and lowering means therefor, a workman's platform on said frame, a horizontal track rail carried by the suspension frame above said platform, a wheeled truck 130 movable on said rail, a motor driven scraper suspended below and pivotally supported

by said truck, a hanger frame supported by the truck, a motor slung in the hanger frame, a tumbling extension on the motor shaft, and a scraping member actuated by said extension.

12. A portable scraping machine comprising a suspension frame, overhead supporting raising and lowering means therefor, a workman's platform on said frame, a horizontal track rail carried by the suspension frame above said platform, a wheeled truck movable on said rail, a motor driven scraper suspended below and pivotally supported by said truck, a hanger frame pivotally supported by the truck, a motor slung in the hanger frame, a tumbling extension on the motor shaft, a scraping member actuated by said extension, a scraper bearing in which said extension is journaled, and means for adjusting said bearing to vary the angle of the tumbling extension and scraping member.

13. A portable scraping machine comprising a suspension frame, overhead supporting raising and lowering means therefor, a workman's platform on said frame, a horizontal track rail carried by the suspension frame above said platform, a wheeled truck movable on said rail, a motor driven scraper suspended below and pivotally supported by said truck, a handle for swinging said scraper on its pivotal mounting, and means for locking said handle.

14. A portable scraping machine comprising a suspension frame, overhead supporting raising and lowering means therefor, a workman's platform on said frame, a horizontal track rail carried by the suspension frame above said platform, a wheeled truck

movable on said rail, a motor driven scraper suspended below and pivotally supported by said truck, and a tilting supporting yoke on the truck on which the hanger frame is pivotally mounted.

15. A portable scraping machine comprising a frame, a substantially horizontal track rail carried by said frame, supporting raising and lowering means for said rail on said frame, a truck movable on said rail, a motor frame pivotally supported on said truck, a motor on the last named frame, and a scraper directly connected to and movable with said motor.

16. A portable scraping machine comprising a frame, a substantially horizontal track rail carried by said frame, supporting raising and lowering means for said rail on said frame, a truck movable on said rail, a motor frame pivotally supported on said truck, a motor on the last named frame, a scraper directly connected to and movable with said motor, and brake mechanism for holding said truck stationary.

17. A portable scraping machine comprising a frame, a substantially horizontal track rail carried by said frame, supporting raising and lowering means for said rail on said frame, a truck movable on said rail, a motor frame pivotally supported on and suspended beneath said truck, a motor on the last named frame, and a scraper directly connected to and movable with said motor.

In testimony whereof I affix my signature in presence of two witnesses.

ARTHUR H. FARGO.
